D. M. DUNNING, JR

METALLIC WEATHER STRIP

Filed March 13, 1926

UNITED STATES PATENT OFFICE.

DAVID M. DUNNING, JR., OF AUBURN, NEW YORK.

METALLIC WEATHER STRIP.

Application filed March 13, 1926. Serial No. 94,503.

This invention relates to metallic weather strips and particularly to those weather strips which are formed to provide a projecting bead designed to be engaged in a groove plowed in the side rails of a window.

It is a well known fact that few windows which have been in use for any length of time remain perfectly true and straight.

The rails of the sash are generally warped 10 outward near the middle and there is considerable shrinkage. While this shrinkage may be compensated for by the addition of ordinary weather-strip material to the jamb of the window, no close adjustment 15 can be made by this method without considerable difficulty and expense.

The warped or bowed condition, however, is much more difficult to overcome and it is rarely corrected due to the fact that ordinary 20 weather-strip material is made straight and rigid and is, of course, so disposed against the jamb, while the mechanic, in plowing the groove in the side face of the sash rail, follows the face of the sash rail as 25 a guide, which results in a groove which is slightly curved from end to end. Obviously, it is impossible for a curved rigid groove to engage properly with a straight rigid rib or bead and even though this curve be relatively 30 slight there is enough to cause the window to bind or else the cross section of the groove has to be made so much larger than the cross section of the rib or bead that there is considerable leakage of air between 35 these two coating members and the object of the weather-strip is defeated.

Another difficulty with the ordinary weather-strip is that when once fastened in place it is difficult to remove and since the 40 sash cannot be removed without removing the weather-strip much of the objection to weather-strips in general comes from mechanics who have occasion to remove a window sash for the purpose of repairing cords, 45 glass, etc.

Furthermore, weather-strips of the character described are ordinarily nailed to the jambs in a rigid position and not capable of easy adjustment and in order to remove 50 the sash it is necessary that these nails be first withdrawn and, as the sash must slide over these nail heads and if a nail works loose it will dig into and damage the sash, it is customary to use coated nails with very 55 thin heads and such nails cannot be withdrawn but must be driven through the metal

with a punch and left buried in the wood.

With these objectionable features in view, the general object of my invention is to provide a ribbed or beaded type of weather-strip which has a certain amount of flexibility and adjustability and is readily removed, which is simple to manufacture and thoroughly effective in operation.

A further object is to provide a weather-strip of this character which includes a channel member of thin metal adapted to be applied against the face of the jamb and attached thereto and provide a weather-strip proper having a bead adapted to be disposed in the groove plowed in the rail of the window sash and which has laterally extending flanges operating within the retainer and having a certain amount of sliding movement therein and a certain amount of lateral movement.

A still further object is to so construct this weather-strip that it will have a certain degree of flexibility so that the bead may be flexed where the groove in the edge face of the sash rail is bowed.

Another object is to provide means whereby the window sash may be readily removed from the jamb without the necessity of removing the retainer from the jamb, it being only necessary to remove the strip proper from its engagement with the retainer.

Other objects will appear in the course of the following description.

My invention is illustrated in the accompanying drawings wherein:

Fig. 1 is a perspective view of a portion of a window frame and sash having my weather-strip applied thereto;

Fig. 2 is a cross sectional view through a portion of the window frame and the weather-strip, the sash being shown in section;

Fig. 3 is a face view of the upper portion of the retainer;

Fig. 4 is a section on the line 4—4 of Figure 3;

Fig. 5 is a section on the line 5—5 of Figure 3;

Fig. 6 is a face view of the weather-strip proper.

Referring to these drawings it will be seen that the retainer which forms the base, as it may be termed, of the weather-strip is made of relatively thin sheet metal and has the form of an elongated strip 10, the lateral edges of which are bent inward toward

the middle line of the retainer as at 11, to thereby form opposed inwardly directed flanges. This retainer 10 has a length slightly greater than the sash with which it is designed to coact. Disposed within the retainer is the weather-strip proper which as illustrated in Figure 6, consists of a strip of thin metal bent upon itself to form the medially disposed hollow bead 12 and the laterally projecting flanges 13. This bead is preferably, though not necessarily, filled with packing 14.

It will be noted that the width of the weather-strip proper at its base is less than the width of the retainer 10 between its flanges 11 and that the opening between the confronting edges of these flanges 11 is greater than the width of the rib so that the weather-strip proper may shift laterally within its base or retainer. This is a very important feature of my invention.

Preferably, and for the purpose of giving flexibility to the weather-strip, the flanges 13 are formed at intervals with inwardly projecting notches or slits 15, these notches or slits being arranged in alternate relation or in staggered relation on opposite margins of the flanges 13.

The channel member 10 or retainer at intervals is formed with depressed portions 16 acting as countersinks for the reception of the headed screws 17 which hold the channel member in place. Preferably, and for the purpose of forming a stop which will limit or prevent any relative sliding movement of the weather-strip proper within the retainer, I slit the flanges 11 adjacent the upper end of the retainer as at 18, and depress these flanges above these slits as at 11*, which can be readily accomplished by means of a screw driver or other suitable tool.

For the sill of the window or for the head of the window I provide a weather-strip consisting of a metal plate or strip 19 having an outwardly protuberant bead 20, having an inner filling 21. This weather-strip 19 is to be attached permanently to the sill or to the head.

I have found that a much better seal is secured between the frame and the weather-strip if the hollow bead or rib be filled with a felt packing. This packing should be made slightly deeper than the hollow rib so that the packing is pressed and forms a tight joint of contact. This packing not only aids in holding the rib from distortion but it also contacts with the channel or base member 10 and thus prevents any possibility of rattling. I do not wish to be limited to the use of this packing or filling 14 in combination with the lateral weather-strips as this may also be used in conjunction with the head or sill weather-strip 19, as shown in Figure 1.

Preferably the channel member 10 is

transversely curved as illustrated in Figure 2, so as to secure a good contact with the jamb and so that as the screws 17 are forced inward this bowed strip will flex and the margins will be forced in a tight engagement with the jamb.

To assemble this weather-strip, the channel or retainer is placed on the jamb and abutted against the parting strip, and is held in place by the screws 17 or other fasteners. The sash can then be placed in position and the ribbed or beaded strip 12 inserted in the retainer and in the corresponding groove which has been plowed in the sash. The weather strip can then be pushed into its proper position. The notches 15 in the base of the weather-strip proper permit a certain amount of flexibility in this member sufficient to allow its being placed in ordinary double hung windows where the length of the sash is more than one-half of the window opening, preferably the weather-strip should be made of sheet metal such as brass, bronze, aluminum or zinc, but it is obvious that other materials might be used and I do not wish to be limited to any specific material for this purpose.

It will be seen that when the window sash is raised or lowered the groove *e* in the sash *E* moves along the protruding rib or bead 12 and the flanges 13 are free to move transversely in the retainer, thus compensating for any irregularities in the sash groove *e* while at the same time air tight joints are secured between the groove *e* and the bead 12 or rib 12 and also between the flanges 13 and the retainer. In cases where the groove *e* has become curved in the warping of the sash, the protruding rib or bead 12, by reason of the fact that these base flanges are notched, will bend with slight resistance and conform to the groove in the sash. I do not wish to be limited to the use of notches 15 in the flanges 13 as the same purpose can be accomplished by forming the weather-strip proper consisting of the bead 12 and the flanges 13 of a plurality of sections which may be simply butted together in place. It is not believed this requires illustration. Other means might be used for securing this result within the scope of my invention as defined by the appended claims.

To remove the weather-strip it is only necessary to open the flanges 11* and withdraw the ribbed member. The sash is then free to be removed from the casing in the usual manner and may be removed and replaced without disturbing the retainer.

While I have illustrated this device as applied to a lower sash it will be understood that it is also adapted to be applied to an upper sash and that it may be applied to any sliding element other than a window where the use of weather-stripping is required.

I claim:—

1. A weather-strip for application to the side edges of sliding window sashes comprising a channel-shaped retainer and a strip having a medial outwardly projecting rib and engaged with said retainer, the ribbed strip having lateral movement within the channel of the retainer, and being formed to have longitudinal flexibility.
  2. A weather-strip for application to sliding windows comprising a longitudinally extending retainer and a weather-strip proper formed to provide a medially disposed rib extending at right angles to the face of the retainer, the retainer and weather-strip being formed to have sliding engagement with each other, and means on the retainer normally preventing said sliding movement of the weather-strip with relation to the retainer but shiftable from its normal position to permit the withdrawal of the weather-strip from the retainer.
  3. A weather-strip for application to sliding windows comprising a longitudinally extending metal strip having inwardly turned lateral flanges and a weather-strip proper formed to provide a medially disposed rib, and laterally extending base flanges at right angles to the rib and disposed beneath the flanges of the retainer, the ribbed strip having lateral movement within said retainer and being formed to have longitudinal flexibility, and means at one end of the retainer preventing accidental longitudinal sliding movement of the weather-strip proper from its engagement with the retainer.
  4. A weather-strip for application to the side edges of sliding window sashes comprising a retainer formed of a longitudinally extending strip of metal having its lateral margins turned inward to form lateral flanges, and a weather-strip proper having a medial hollow rib extending at right angles to the flanges and the rib and lateral flanges, the rib and flanges being formed from a single strip of metal, the base flanges of the weather-strip having a width less than the channel of the retainer and the rib at its junction with the flanges being less in width than the distance between the flanges of the retainer whereby said weather-strip proper may have lateral movement, the lateral flanges of the weather-strip proper having inwardly extending slits at intervals to secure longitudinal flexibility of the weather-strip proper.
  5. A weather-strip formed of a strip of metal bent along a medial line to form an outstanding hollow rib, and a yielding filling disposed within said hollow rib and terminating at the base of said rib.
  6. A weather-strip formed of a strip of metal bent along a medial line to form an outstanding hollow rib, and a yielding fill-
- ing disposed within the rib consisting of a layer of felt, the layer terminating approximately flush with the outer surface of the lateral flanges.
7. A weather-strip consisting of a strip for the side edges of sliding window sashes of metal bent along a medial line to provide an outwardly projecting hollow rib and laterally projecting flanges, the lateral margins of the flanges being slit at intervals to secure longitudinal flexibility of the weather-strip.
  8. A weather-strip for application to the side edges of sliding windows comprising a retainer formed of a strip of metal having its side margins inwardly turned to form guiding flanges, the strip having apertures at intervals for the passage of fastening devices whereby the strip may be held to a window casing, and a weather-strip proper having a medially disposed rib and laterally projecting flanges disposed beneath the flanges of the retainer, one end of the retainer being formed to normally prevent the withdrawal of the weather-strip proper from the retainer.
  9. The combination with a window frame and a sash slidably engaging the same and having a longitudinally extending groove, of a weather-strip comprising a retainer attached to the frame and consisting of a longitudinally extending strip of metal, and a weather-strip proper having an outwardly extending medial rib slidably engaging the groove in the side of the sash and slidably engaging the retainer, the weather-strip having lateral movement with reference to the retainer, said weather-strip being transversely slotted at intervals to thereby secure flexibility for the strip.
  10. The combination with a window frame and a sash sliding therein and having a longitudinally extending groove confronting the frame, of a weather-strip for application thereto comprising a retainer consisting of a longitudinally extending strip of metal attached to the frame, and a weather-strip proper slidably engaging the retainer and having a longitudinal outwardly extending rib slidably engaging the groove in the sash, and means at one end of the retainer normally preventing longitudinal sliding movement of the weather-strip with relation to the retainer but shiftable to permit the weather-strip to be slid out of the retainer and out of the sash groove.
  11. A weather-strip of the character described comprising a retainer formed of a strip of metal and having its side margins inwardly turned to form guiding flanges, the strip being transversely bowed and having apertures at intervals for the passage of fastening devices through the middle of the strip whereby the strip may be held to a window casing with its side margins bear-

ing tightly against the window casing, and a weather-strip proper having a medially disposed rib and laterally projecting flanges disposed beneath the flanges of the retainer,
5 the rib being narrower than the distance between the edges of said retainer flanges and the weather-strip proper having a width less than the width of the retainer whereby the weather-strip proper may shift laterally in

either direction, one end of the retainer 10 having means to normally prevent the withdrawal of the weather-strip proper from the retainer to permit said withdrawal when it is desired to remove the sash from the window.

15

In testimony whereof I hereunto affix my signature.

DAVID M. DUNNING, JR.
